A. W. SUMMER.
THRESHING MACHINE.

Patented Mar. 21, 1831.

Abraham W. Summers, of Gates, N. York,
Letters Patent.

The schedule referred to in this Letter Patent and making part of the same containing a description in the words of the said Abraham W. Summers, himself of his Improvement, called the float and tooth threshing machine.

To all and to whom these presents shall come, Abraham W. Summers of the town of Gates and County of Monroe and State of New York, -- Be it known that I Abraham W. Summers have invented a new and useful improvement in threshing machines not known or used before my application.

This Machine like all others of the same kind consists of posts, girts, cylinders, pulleys &c, and differs but little from that kind of Machine which has a cylinder with teeth and a concave bed with bars. The improvement in this machine consists in an increased size of cylinder, the diameter is fourteen inches and a row of teeth and a float, alternate dividing the surface into twenty eight equal parts. The floats are made of band iron and let in between the lagging and fastened with screws to the edge of each where they are put on the cylinder, and project five eights from the surface between each of these floats there is a row of teeth of three eights round iron, and placed one inch from center to center and project one inch from the surface, making the full diameter eighteen inches, and the teeth in one row covers the space in the other, or its proportion of it the principal use of these floats is to prevent the straw forming a wisp around the cylinder (which will be the case when the straw is a little wet) also helps to keep the straw close to the concave bars, the concave is a full quarter circle from the feeding upon - this concave is formed of bar iron wrought diamonding of one inch square running parallel with

the flats, and rows of teeth, so placed that a line passing through the acute angles, will lead to the center of motion and placed as near together as to prevent the white cap passing between the obtuse angles, leaving an eighth of an inch between the acute angle and the teeth when in action, the principal features of this improvement are as follows. first the placing of the flats between the rows of teeth which prevent but wheat or straw forming a wisp around the cylinder, secondly the bars of the concave made diverging and the acute angle placed within one eighth of an inch of the teeth and so close together as to prevent the white cap passing between them, thereby every kernel is compelled to pass over the whole concave which clears it from chaff and bran and does not cut the Kernel. All the above improvements are relied on together with the knowledge of varying the proportion, and material as may best suit any fancy, so that all the while I adhere to my principle and do not part from it.

In testimony whereof I have hereunto subscribed my name this 12th day of February 1831
Witness.
